Primary Examiner — Philip S Hyder*Assistant Examiner* — Cary M Robinson(74) Attorney, Agent, or Firm — Finnegan, Henderson, Farabow, Garrett & Dunner LLP(57) CLAIM

The ornamental design for a display screen with icon, as shown and described.

DESCRIPTION

The broken lines of uneven length show the display screen and form no part of the claimed design.

1 Claim, 1 Drawing Sheet(56)
